2 Claims. (Cl. 123—48)

Our invention relates to improvements in Diesel engines. The objects of the invention are to provide means whereby the opening of the air inlet and exhaust outlet may be varied to suit the requirements of engine load; to provide for adjustment of the compression within the cylinder when the engine is at rest or in operation; to provide novel means for building up scavenging air pressure during outward and inward strokes of the engine pistons, and to provide an engine frame of welded plate construction, thus reducing the frame weight below that prevailing in the conventional cast iron frame construction and also reducing the cost.

The invention consists of an engine having opposed pistons within a single cylinder, a rocker arm movement between the pistons and a crank shaft wherein the fulcrum of one of the rocker arms is adapted for movement to vary the position of the stroke of one of said pistons, as will be more fully described in the following specification and shown in the accompanying drawings, in which—

Fig. 1 is a sectional view of the invention taken transversely to the crank shaft.

Fig. 2 is a sectional view taken on the line 2—2 of Figure 1.

Fig. 3 is a sectional view through the cylinder taken on the line 3—3 of Figure 1.

Fig. 4 is a sectional view through the cylinder taken on the line 4—4 of Figure 1.

Fig. 5 is a sectional view through the cylinder taken on the line 5—5 of Figure 1.

Fig. 6 is a transverse sectional view of the scavenging air pump taken on the line 6—6 of Figure 2.

In the drawings like characters of reference indicate corresponding parts in each figure.

The numeral 1 indicates generally a base having a curved plate 2 which forms a portion of the crank case 3. Front and rear walls numbered 4 and 5 respectively are welded to the base and detachable end walls 6 and 7 are fitted to enclose the engine. Welded between the walls 4 and 5 are cylinder cradle or division plates 8 and 9, the plates 8 serve to support the cylinder assembly to be hereinafter described and to separate it from the crank case 3. Most of the walls and other parts of the base are cut from plane sheet material.

The cylinder assembly consists of a cylinder 11 and a water jacket 12. The cylinder 11 is provided at one end with intake ports 14 some of which are radial and some tangential to the cylinder wall and adjacent the opposite end

of the cylinder exhaust ports 15 are provided. The webs 16 between the exhaust ports 15 are cored to provide water passages 17 between different portions of the water jacket 12, see Figure 4. At the centre of the cylinder openings are formed to accommodate an injector 19 and a compression release and fuse plug holder 20. Communication with the water jacket is made through circulation pipes 22 and 23. An opening 25 is formed in the rear plate 5 through which air is admitted to an air jacket 26 surrounding the cylinder 11.

Mounted in bearings 28 is a crank shaft 29 which is provided with diametrically opposed cranks 30 within the crank case. A fly wheel 31 is fitted to the crank shaft beyond the plate 5, see Figure 2.

The cylinder 11 is provided with two pistons 33 and 34 each having a detachable head 35 which is so fitted as to provide an annular space 36 between the head and the piston. This head may, being so spaced, expand freely in response to heat transfer during the firing stroke without unduly expanding the piston, thereby eliminating the sticking of piston rings and scoring of cylinder walls.

The pistons 33 and 34 are fitted with short connecting rods 37 to rocker arms 38 and 39 respectively. The rocker arms are connected in turn by connecting rods 40 and 41 to the opposing cranks 30. The rocker arm 38 is journaled upon a shaft 42, see Figure 1, and the rocker arm 39 is journaled upon a shaft 43 which is mounted in eccentrics 44 which are in turn journaled in bearings 45 in the plates 4 and 5, one only being shown. The shaft 43 and the eccentrics 44 are adapted to be rocked through approximately 90 degrees by a lever 47 which is fitted with a locking screw 48 to permit said lever to be held firmly in any adjusted position.

The plate 5 is provided with an elongated slot 49 through which the rock shaft 50 of an air pump 52 extends. The pump consists of a circular drum 53 having inner and outer walls 54 and 55 respectively, see Figures 2 and 6, and is mounted within a housing 56 attached to the outside of the plate 5. The drum is provided with opposed segmental intake chambers 57 each having an intake 58 in the outer wall 55 and a lightly spring loaded valved inlet 59, which communicates through the slot 49 with the crank case. The inlets 59 serve as breathers to the crank case and admit oil containing air from the crank case to the pump to lubricate it. The side walls 60 of each intake chamber are provided with spring

loaded valves 62 to admit air to the drum. The shaft 50 is provided with radial wings 63 which on being rocked sweep the air admitted towards and through spring loaded outlet valves 65 into the interspace between the drum 53 and the walls of the housing 56 which communicates through the opening 25 into the jacket 26 and the cylinder 11. The rock shaft 50 of the air pump is fitted within the crank case with a forked lever 67 through which it is rocked by the rocker arm 38 through a connecting rod 68.

Fuel oil is supplied to the injector 19 from a suitable feed pump 69 which is operated by a cam 10 which is driven by a chain and sprocket driving train 71 from the main crank shaft 29.

When the engine is to be used for marine purposes or in other situations where the load is substantially constant, adjustment may be made to the position of the cylinder 11 within its supports in order for it to give its greatest efficiency at the desired load by the following means. Supposing it should be necessary in order to get the desired efficiency that the air intake ports 14 open late and the exhaust ports 15 open early, the cylinder 11 and its water jacket would be moved toward the left, as viewed in Figure 1, by adjusting the nuts 73 which pass through a lug 74 secured to the cylinder 11. In this position the intake would be late in opening and early in closing and the exhaust would be early in closing and late in opening. This adjustment will fit the engine to its particular load condition. The adjustment of fuel feed will have the usual effect on the engine.

In small engines particularly, starting is facilitated by raising the compression by setting the lever 47 to the position shown in the drawings. By so doing the heat of compression of the air admitted is increased and the ignition of the charge is therefore more certain. When the engine is running normally and at normal temperatures the compression may be advantageously reduced by swinging the lever 47 towards its horizontal position because the piston heads and other

surfaces are hot enough to promote ignition at the proper time.

When it is desired to troll or maintain low speed for lengthy periods, the compression is again increased, thus preventing missing and knocking which is frequent in engines with constant compression.

By providing detachable heads 35 to the pistons with an interspace between them there is but little heat transfer from the heads and their heat is maintained to insure effective firing of the compressed charges of combustible vapour within the cylinder.

What we claim as our invention is:

1. In a Diesel engine having an engine frame, a cylinder, two opposed pistons in said cylinder, a crank shaft having opposed cranks, a pair of rocker arms journalled upon shafts parallel to said crank shaft, each of said rocker arms being operatively connected to a piston and one of said cranks, one of said rocker arm bearing shafts being mounted in eccentrics, a lever for rocking the eccentrics and means for locking the eccentrics in adjusted position, said engine frame having front and rear plates enclosed at their ends to form a crank case, division plates extending between said plates forming a cradle for the cylinder.

2. In a Diesel engine having an engine frame, a cylinder, two opposed pistons in said cylinder, a crank shaft having opposed cranks, a pair of rocker arms journalled upon shafts parallel to said crank shaft, each of said rocker arms being operatively connected to a piston and one of said cranks, one of said rocker arm bearing shafts being mounted in eccentrics, a lever for rocking the eccentrics and means for locking the eccentrics in adjusted position, said engine frame having front and rear plates enclosed at their ends to form a crank case, division plates extending between said plates forming a cradle for the cylinder.

3. In a Diesel engine having an engine frame, a cylinder, two opposed pistons in said cylinder, a crank shaft having opposed cranks, a pair of rocker arms journalled upon shafts parallel to said crank shaft, each of said rocker arms being operatively connected to a piston and one of said cranks, one of said rocker arm bearing shafts being mounted in eccentrics, a lever for rocking the eccentrics and means for locking the eccentrics in adjusted position, said engine frame having front and rear plates enclosed at their ends to form a crank case, division plates extending between said plates forming a cradle for the cylinder, and said front and rear plates forming a support for the crank shaft bearings.

WILLIAM WAGNER.

JOHN SWANN.
